UNITED STATES PATENT OFFICE.

JOHN ELLIS PEARSON, OF MOTOR, NORTH CAROLINA.

TELEGRAPHIC KEY.

SPECIFICATION forming part of Letters Patent No. 778,067, dated December 20, 1904.

Application filed November 12, 1903. Serial No. 180,862.

To all whom it may concern:

Be it known that I, JOHN ELLIS PEARSON, a citizen of the United States, and a resident of Motor, in the county of Polk and State of North Carolina, have invented a new and Improved Telegraphic Key, of which the following is a full, clear, and exact description.

My invention relates to telegraphic keys, my more particular object being to produce a key which is self-closing—that is to say, a key in which the main-line circuit is normally closed the instant the operator removes his hand from the key-button.

Reference is to be had to the accompanying drawings, forming a part of this specification, in which similar characters of reference indicate corresponding parts in all the figures.

Figure 1 is a plan view showing the key equipped with my invention. Fig. 2 is a side elevation, partly broken away, of the same. Fig. 3 is a horizontal section upon the line 33 of Fig. 2 looking in the direction of the arrow. Fig. 4 is a diagram of the electric circuit, and Fig. 5 is a side elevation of the lip 17 and its connections viewed as from the right of Fig. 1.

The base-ring is shown at 1, the key-legs at 2 3, the clamping-nuts at 4 5, the trunnion-posts at 6, the trunnion-screws at 7, and the locking-screws at 8 9, these parts being of the usual construction. The key-lever is shown at 10 and is provided with trunnions 11, which are engaged by the trunnion-screws 7, these parts being of the usual construction. A tension-spring 12 is connected with the base-ring 1 and is engaged by a tension-screw 13, which is provided with a locking-screw 14. An insulating-sleeve 15, made preferably of hard rubber, is mounted within and partially above the base-ring 1. The nipple 16 is connected electrically with the leg 3, and immediately below this nipple and encircling the leg 3 is a closure-lip 17, which may be of the usual construction. The contact-points are shown at 18 19 and may be of platinum or any desired material. A wire 20 is used for the purpose of closing the circuit, as hereinafter described. The key-button is shown at 21. Below the button is a nut 22 encircling the stem 23. This stem is provided with spring contact

members 24 of the shape shown, these contact members being provided at their upper ends with hooks 25 26. An insulating member 27 of mushroom shape is provided with an integral stem 29, which engages a contact-plate 28. The member 27 is loosely fitted into the cylindrical aperture 30 of the shape shown. A spring 31 is disposed within the lower portion of this aperture and rests upon a disk 32 of insulating material. Resting upon this spring is an insulating - disk 33, which is pressed upward and into engagement with the plate 28, thereby forcing this plate into contact with the hooks 25 26. The plate 28 is integrally provided with a stem 35, which projects outward through a horizontal slot 34 and is engaged by a binding-screw 36 whereby the wire 20 is connected thereto. The battery is shown at 38 and is connected by wires 37 39 with the leg 3 and the key-lever 10, respectively. A flattened sleeve 40, of conducting material, is connected with the wire 20 and is slipped over the lip 17, so as to effect electrical communication between the wire 20 and the lip 17. The mechanical contact-screw 41 is of the usual construction and may rest upon the leg 2, if desired.

The operation of my invention is as follows: The spring 31, by forcing the disk 33 upward, normally presses the plate 28 into engagement with the hooks 25 26, thereby completing a circuit through the lever 10, stem 23, hooks 25 26, plate 28, wire 20, lip 17, leg 3, and wire 37 to the battery 38, whence the current flows through wire 39 to the key-lever 10. When, however, the operator grasps the button 21, he normally places his forefinger upon the member 27 of mushroom shape, thereby depressing the same and breaking the contact between the hooks 25 and 26 and the plate 28. This opens the main circuit. If, however, the key be depressed in the usual manner, the contact 19 closes upon the contact 18, thereby completing the circuit. The manipulation of the key is therefore substantially unchanged, the only difference being that the operator must use a little care to depress the member 27. He cannot neglect to do this, for the reason that the key will not operate at all unless the member 27 be depressed. When

the operator is through telegraphing, he merely releases the key, whereupon the circuit is closed automatically by the upward pressure of the spring 31, as above described.

5 No matter how careless the operator may be he is utterly unable to leave his key open when the key is equipped with my device.

As the sleeve 40 detachably engages the lip 17, all that is necessary to apply my invention

10 to a key already in use is to provide the same with a new finger-button substantially of the kind shown and to slip the sleeve 40 over the lip 17, with which every ordinary key is provided.

15 Having thus described my invention, I claim as new and desire to secure by Letters Patent—

1. In a self-closing telegraphic key, the combination of a key-lever, a finger-button of insulating material mounted thereon, contact mechanism connected with said finger-button and adapted to open by finger-pressure, a member connected with said contact mechanism and free to be operated by the fingers so as to actuate said contact mechanism, a lip of 20 conducting material disposed adjacent to said key-lever and insulated therefrom, except when said key-lever is depressed, a conducting member detachably engaging said lip, and a connection between said conducting member 25 and said contact mechanism.

2. In a self-closing telegraphic key, the combination of a fixed base portion provided with a lip and with a contact-point in electrical communication with the same, a lever mov-

able relatively to said base portion and provided with a contact-point mating that of said base portion, a finger-button mounted upon said key-lever, contact mechanism connected with said finger-button and opened and closed by finger-pressure, a flattened sleeve detachably encircling said lip, and a conductor connecting said flattened sleeve with said contact mechanism. 35

3. An attachment for telegraphic keys, comprising a sleeve for detachably engaging the lip of an ordinary key, a finger-button provided with contact mechanism, a connection between said contact mechanism and said sleeve, and means for securing said finger-button upon an ordinary key-lever. 45

4. An attachment for telegraphic keys, comprising a flattened sleeve for encircling the lip of an ordinary key, a finger-button provided with means whereby it may be mounted upon a key-lever, said finger-button being also provided with contact mechanism, and a detachable connection between said sleeve and said contact mechanism for closing the circuit independently of the movements of the key-lever. 55

In testimony whereof I have signed my name to this specification in the presence of two subscribing witnesses.

JOHN ELLIS PEARSON.
